UNITED STATES PATENT OFFICE

WILFRED I. OHMER, OF DAYTON, OHIO

SAFETY RAZOR

Application filed January 26, 1931. Serial No. 511,185.

This invention relates to improvements in safety razors.

The essential object which I have in view is to combine with the head or main body 5 plate of the razor, a handle adapted to be positioned at substantially a right angle to the head when the razor is being used to shave, and to be swung or adjusted into a position substantially parallel with the head 10 when the razor is to be put in a small box or to be carried in the pocket, and to combine with these parts a suitable fastening device to secure the handle in its right angle position and to release it to enable it to be 15 swung into its parallel position.

By virtue of these improvements I produce a safety razor which, when not in use, may be folded in the manner stated to bring its parts within a small compass for convenience, as when carried in one's pocket.

In the accompanying drawing,

Figure 1 is a plan view of my improved razor with its handle in working position.

Figure 2 is a horizontal sectional view 25 through the razor and its handle and fastening device.

Figure 3 is a longitudinal sectional view taken on the line 3—3 in Figure 1.

Figure 4 is a similar view to Figure 1, but 30 with the handle adjusted to its parallel or packing position.

Figure 5 is an elevation looking at the clamping plate with its comb or teeth, with the handle and its fastening parts in cross-section, on the line 5—5 of Fig. 1.

Fig. 6 is a sectional view on the line 6—6 of Figure 1 showing the collar and handle, on an enlarged scale.

Fig. 7 is a detail perspective view of the 40 collar.

Referring to the drawing, the numeral 1 indicates the head or major body of the razor. It is of conventional form being in outline in the nature of a parallelogram. Its distinctive feature is, however, the addition of a threaded stud indicated at 2, which extends from the head, and is preferably integral therewith. The office of this threaded stud is that of furnishing a means upon which a collar 3 is mounted or secured.

As more clearly seen in Figures 5 and 7, this collar has a flat shank 4 adapted to enter in the space between the bifurcations 5 of the handle 6. In order to pivot the handle bifurcations to the shank 4, pivot pins 7 are inserted through openings in the bifurcations and thence into the shank 4, as seen in Figure 3.

A blade-clamping plate or comb 8 is placed on the stud 2 between the collar 3 and the head 1, so that a blade 9 may be clamped between the comb and the head.

Referring now to one fastening means for connecting the handle rigidly with the shank 4 of the collar 3, it will be noted that the numeral 10 indicates a pin or bolt-like device. The handle proper is hollow to receive this pin. Its outer end is equipped with a knurled finger piece 11 secured as by a pin 12, so that one can rotate the pin by applying his fingers to this knurled piece. The other end is threaded as indicated at 13 and adapted to be screwed into the shank 4 of the collar 3.

Thus when the razor is to be used for shaving the handle is rigidly positioned and held as seen for instance in Figure 1. But when the handle is to be folded with respect to the head, as seen in Figure 4, the pin 10 is manipulated by the knurled piece 11 and screwed out of the shank of the collar 3, and will occupy the position shown in Figure 4. In swinging the handle from its right angle to its parallel position, with respect to the head, the handle turns on the pivots 7, which are eccentrically positioned as seen in Figures 1, 4 and 5, the more readily to permit the handle to swing up closely to the general head of the device.

I would have it understood that the particular fastening means here described is the preferable one, but that any other fastening means applicable is contemplated and is within my invention.

It will now be seen that the parts of this improved razor may be readily assembled, and due to their simplicity are capable of economical production; that either a special form of head piece and comb, between which the razor blade is held, may be used, or that

the now rather common or conventional types of head pieces and comb pieces may be combined with my handle device.

The chief features to which my invention is directed are the means for pivoting the handle on its mounting, and a fastening means by which the handle is held firmly against any swinging movement when the razor is to be used, but which means will 10 permit of quickly unlocking the handle so that it may swing on its pivots and be placed substantially parallel to the head to reduce its compass for purposes of utilizing a small container or otherwise making it convenient 15 to be placed in one's pocket if that be desired.

It will be understood that I desire to comprehend within the scope of my invention all the modifications necessary to adapt it to 20 varying conditions and uses.

Having thus fully described my invention, what I claim as new and desire to secure by Letters Patent, is:

1. In a razor, the combination with a head, 25 a threaded stud integral therewith, a threaded collar adapted to be screwed on said stud, a clamping plate adapted to be urged to clamping position by the collar, a shank on the collar, a handle pivoted on the shank, 30 and a fastening device comprising a pin having a threaded end extending through the handle and adapted to be threaded into and out of the collar, to fasten and unfasten the handle.

2. In a razor, the combination with a head, 35 a threaded stud integral therewith, a threaded collar mounted on said stud, a clamping plate between the collar and the head, a shank extending from the collar, a handle 40 pivoted to the shank with its point of pivot eccentric to the longitudinal center of the handle, and a fastening device comprising a pin having a threaded end extending through the handle and operable at the outer 45 end to engage and disengage the pin with threads in the collar.

3. In a razor, a head, a stud extending 50 therefrom, a collar adapted to be screwed onto the stud, a handle pivoted to said collar, and a plunger in said handle for holding the handle in a fixed position on the head, said collar having a hole therein to receive the plunger.

4. In a razor, a head having a threaded 55 stud thereon, a collar having a threaded opening, said stud being threaded into one end of said opening, a bifurcated hollow handle pivoted to said collar, and a pin in said handle adapted to be threaded into the 60 other end of said threaded opening to hold the handle rigidly on the head.

In testimony whereof, I affix my signature.
WILFRED I. OHMER.
